UNITED STATES PATENT OFFICE.

CHARLES M. BROWN, OF PLATTSBURG, MISSOURI.

COMBINED RAIL TIE AND FASTENER.

1,117,635.

Specification of Letters Patent.

Patented Nov. 17, 1914.

Application filed August 19, 1914. Serial No. 857,546.

To all whom it may concern:

Be it known that I, CHARLES M. BROWN, a citizen of the United States, residing at Plattsburg, in the county of Clinton and State of Missouri, have invented certain new and useful Improvements in Combined Rail Ties and Fasteners, of which the following is a specification, reference being had to the accompanying drawings.

10 This invention relates to new and useful improvements in combined rail ties and fasteners, and an object of the invention is the provision of a device of this character which comprises a minimum number of parts 15 whereby the same may be cheaply manufactured, the device being highly efficient and durable in use.

Another object of this invention is the provision of a combined rail tie and fastener which includes a metallic tie the tie comprising an elongated plate of metal which is bent longitudinally to provide a base wall and spaced side walls, transversely disposed supporting plates being secured 25 upon the upper edges of the side walls of the tie adjacent its ends, to slidably receive rail chairs by means of which the rails of the track are connected to the tie without the use of bolts and nuts.

30 With these and other objects in view, my invention consists in the novel construction, combination, and arrangement of parts to be hereinafter more fully described, claimed, and illustrated in the accompanying drawings, in which—

Figure 1 is a longitudinal sectional view through one of my improved ties showing the rails connected thereto; Fig. 2 is a top plan view thereof; Fig. 3 is a perspective 40 view of one of the rail chairs; Fig. 4 is a perspective view of the tie; Fig. 5 is a perspective view of the locking key; and Fig. 6 is a transversional view through my improved tie; and Fig. 7 is a perspective view 45 of an alternative form of my invention showing the same used in connection with a rail joint.

Referring more particularly to the drawings, the numeral 1 designates my improved 50 tie which consists of an elongated plate of metal bent longitudinally adjacent its side edges to provide a base wall 2 and upstanding spaced parallel side walls 3. Disposed transversely of the tie and secured at their 55 opposite ends to the upper edges of the side walls of the tie are supporting plates 4, the

plates being disposed adjacent the opposite ends of the tie to support the rails of the track. Each side wall of the tie is formed with a pair of recesses 5 in their upper edges, the recesses in each side wall being formed to partially extend under the side edges of one of the plates at one end thereof, the pairs of recesses being formed in opposite side walls of the tie for a purpose to be hereinafter more fully described. Formed on each plate at its end opposite to that which extends above the recesses, is an upstanding lug 6, and a key receiving opening 7 is formed in each supporting plate adjacent one side edge thereof.

The numeral 8 designates the rail chairs upon which the rails 9 are disposed for connection to the tie, each of the rail chairs having a pair of rail engaging lugs 10 formed thereon at diagonally opposite corners, for engagement with the base flanges of the rails. The opposing corners of the lugs on each chair are cut away to provide parallel faces 10', which are spaced apart a distance slightly greater than the width of the base flanges of the rails, so that the chairs may be applied to the rails at any point along their length by turning the chairs so that the faces 10' are arranged on opposite sides of the rails, whereby the chairs may be moved upwardly to dispose the rail engaging lugs 10 above the base flanges, so that upon turning of the chairs to extend longitudinally of the rails, the lugs 10 will be engaged with the base flanges of the rails. The chairs are provided on their under faces at their opposite end edges with inturned flanges 11 which extend the entire width of the chairs, the flanges 11 being adapted for engagement with the side edges of the supporting plates 4, the recesses 5 being of sufficient depth to permit of the engagement of the flanges with the plates.

Formed in each chair 8 is a key receiving opening 12, the openings 12 being adapted to register with the openings 7 in the supporting plates when the chairs are in a position for use, and adapted for disposition through the registering openings 7 and 12. are locking keys 13 which consist of rectangular metallic plates, split at their opposite ends to provide wings 14 and 14'. The wings 14 on the lower ends of the plates 110 are bent in opposite directions to extend laterally of the plates, whereupon the plates

are disposed through the registering openings, so that the wings 14 on the lower ends of the plates engage the under faces of the plates 4, and so that the wings 14' on the upper ends of the plates may be also bent in opposite directions to engage the upper faces of the chairs, whereby the chairs 8 are locked to the supporting plates and are prevented from backing off of the same.

10 In Fig. 7 of the drawings, I have illustrated an alternative form of my invention, in which my improved device is shown in connection with the rail joint. In this view, the meeting ends of a pair of rails 15 are connected together by the angle bars 9^a are connected together by the angle bars 15, in the lower edges of which recesses 16 are formed, which are of substantially the same shape as the rail engaging lugs 10^a of the chairs 8^a, so that upon engagement 20 of the angle bars 15 with the rails, the chairs 8^a are locked in position upon the rails without the use of any fastening devices by reason of the engagement of the lugs 10^a in the recesses 16 in the angle bars.

25 From the above description taken in connection with the accompanying drawings, it will be seen that I have provided a combined rail tie and fastener in which the rail chairs may be connected to the rails 30 at any point along their length after the rails have been laid upon the ties, by disposing the chairs below the rails between adjacent ties, with the flat faces 10' of the lugs on opposite sides of the base flanges 35 of the rails, so that the chairs may be moved upwardly and turned to engage the lugs with the base flanges, whereupon the chairs are moved longitudinally of the rails to engage the flanges 11 with the side edges 40 of the plates 4. It will be seen that the sliding movement of the chairs with relation to the plates 4 is limited by the engagement of one edge of the plates with the lugs 6, whereupon the keys may be disposed through the registering openings 45 and 12 in the hereinbefore described manner to lock the chairs to the supporting plates. By the provision of a rail tie and fastener which is constructed in accordance 50 with my invention, the use of bolts and nuts to connect the chairs together and to connect the chairs with the ties is eliminated whereby the time required heretofore in laying the track is materially reduced.

55 Having thus fully described my invention, what I desire to claim and secure by Letters Patent is:—

1. In combination with a tie having spaced vertical side walls, said tie having

transversely extending supporting plates secured to the upper edges of the side walls adjacent the ends of the tie, said side walls having recesses therein which partially extend under the side edges of the plates at one end thereof, of rail chairs having in-turned flanges on their under faces for sliding engagement with the side edges of said plates, and means for limiting the inward movement of the chairs upon said plates.

2. In combination with a tie having 70 spaced vertical side walls, transversely disposed plates secured to the upper edges of the side walls adjacent the ends of the tie, said side walls having recesses formed therein which extend under the side edges of the 75 plates at one end thereof, of rail chairs having in-turned flanges for sliding engagement with the side edges of the plates, means for limiting the inward movement of said chairs with relation to the plates, and means for locking the chairs to said tie in their operative position.

3. In combination with a tie having upstanding parallel side walls, transversely disposed plates secured at their ends to 85 the upper edges of the side walls of the tie adjacent its ends, each of the side walls having a pair of recesses formed therein partially extending under the side edges of one of the plates, the recesses in the side 90 walls being arranged on opposite sides of the tie, of rail chairs having in-turned flanges for sliding engagement with the side edges of the plates, an upstanding flange formed on the other end of each plate to 95 limit the inward movement of said chairs, and means for locking said chairs to said plates when the chairs have reached the limit of their inward movement.

4. In combination with a tie having transversely disposed supporting plates on its upper face adjacent the ends of the tie, of rail chairs having in-turned flanges for sliding engagement with the side edges of the plates, means for limiting the inward movement of the chairs on said plate, said plates and said chairs having openings therein adapted to register when the chairs have reached the limit of their inward movement, and means adapted to be engaged 110 through said registering openings to lock said chairs to said plates.

In testimony whereof I hereunto affix my signature in the presence of two witnesses.

CHARLES M BROWN.
